(57) **CLAIM**

The ornamental design for a ground penetrating radar, as shown and described.

DESCRIPTION

1.-2. Ground penetrating radar

1.1 : Perspective

1.2 : Front

1.3 : Back

1.4 : Left

1.5 : Right

1.6 : Top

1.7 : Bottom

2.1 : Perspective

2.2 : Front

2.3 : Back

2.4 : Left

2.5 : Right

2.6 : Top

2.7 : Bottom

In the drawings, the broken lines depict portions of the ground penetrating radar that form no part of the claimed design.
